CLAIM

The ornamental design for a multi-function printer, as shown and described.

DESCRIPTION

FIG. 1 is a top, left perspective view of a multi-function printer showing our new design;

FIG. 2 is a front elevation view of FIG. 1;

FIG. 3 is a left side elevation view of FIG. 1;

FIG. 4 is a right side elevation view of FIG. 1;

FIG. 5 is a top plan view of FIG. 1; and,

FIG. 6 is a partially enlarged top plan view thereof at the location surrounded by the dot-dash broken lines A of FIG. 5.

The broken lines in the figures represent portions of the multi-function printer that form no part of the claimed design. The dot-dash broken line markers in FIGS. 5 & 6 delineate portions of the multi-function printer that are shown enlarged in FIG. 6. The dot-dash broken lines form no part of the claimed design.
